J. C. HERRON

COLOR SCREEN PROTECTION AND SUPPORT

Filed Dec. 7, 1921

Inventor:

James C. Herron

by Albert Scheibl
Attorney

UNITED STATES PATENT OFFICE.

JAMES C. HERRON, OF CHICAGO, ILLINOIS, ASSIGNOR TO REFLECTOR & ILLUMINATING CO., OF CHICAGO, ILLINOIS, A CORPORATION OF ILLINOIS.

COLOR-SCREEN PROTECTION AND SUPPORT.

Application filed December 7, 1921. Serial No. 520,462.

To all whom it may concern:

Be it known that I, JAMES C. HERRON, citizen of the United States, residing at Chicago, in the county of Cook and State of Illinois, have invented certain new and useful Improvements in a Color-Screen Protection and Support; and I do hereby declare the following to be a full, clear, and exact description of the invention, such as will enable others skilled in the art to which it appertains to make and use the same.

My invention relates to lighting equipment and more particularly to means for varying the effective color of the light projected by reflectors used in connection with the lamps.

In stage lighting, it is quite customary to secure at least a portion of the desired illumination by means of so-called border lights suspended in the wings of the stage, and it is highly desirable that the light from the border lamps should be varied in color according to the requirements of the scene. Border light arrangements of the trough type have heretofore been employed for this purpose with color-screens laid across the mouth of the entire trough, but have proven objectionable both on account of the difficulty of handling such large color screens and on account of the likelihood of accidents from their breakage. Moreover, the trough arrangement has not proven as efficient in projecting the light as the use of suitably shaped individual reflectors over the various lamps, and in the interests of efficiency it is highly desirable that the more efficient plan of using individual reflectors over the lamps should be employed even when the light is to be colored.

In one of its objects, my invention aims to provide simple and effective means for supporting color-screens in connection with reflectors for this purpose, and aims to arrange such supporting means so that the color-screens can easily and quickly be removed or replaced. It also aims to provide simple and effective means for preventing accidents by guarding against the dropping of any portion of the color-screen in case the latter should be cracked by the heat of the lamp. Moreover, my invention aims to provide such color-screen supporting and protecting means in a form which can

readily be employed in connection with an ordinary socket and reflector without requiring any changes in either the reflector or the socket proper, and aims to include resilient or yielding members in the supporting arrangement so as to compensate for any irregularities in the size of the reflector and socket arrangement or in the thickness of the color screen. Furthermore, it aims to provide an arrangement for this purpose in which the color screen can be removed and replaced without detaching any part of the holder from the lighting equipment, but in which certain portions of the holder can also be easily and quickly detached whenever this should seem desirable. It also aims to provide guard means for preventing a dropping wing or fly from catching on the color-screen holder, and desirably aims to arrange part of the supports for the holder so that they will act as such a guard. Still further and also more detailed objects will appear from the following specification and from the accompanying drawings, in which—

Fig. 1 is a fragmentary front elevation of a portion of a border lighting unit comprising a conduit carrying a variety of sockets each equipped with an angle reflector and with a color-screen holding and projecting appliance embodying my invention and including four yielding links.

Fig. 2 is a transverse vertical section through the same taken along the correspondingly numbered line of Fig. 1, a part of the holder being broken away to show the position of the color screen and of the transparent safety guard below this screen.

Fig. 3 is a view similar to the lower portion of Fig. 2, but showing the holder partly detached from the supporting links to permit the color screen to be removed or inserted.

Fig. 4 is an elevation showing another embodiment of my invention, namely one in which two links support the holder and are secured by a clamp to the neck of the reflector.

Fig. 5 is a fragmentary section of a holder, showing a gelatin color screen interposed between a wire-glass guard plate and an upper clear glass plate.

In the embodiment of Figs. 1, 2 and 3, I

am showing my invention as employed in connection with a row of sockets 1 bolted to a metal conduit 2 which houses the wiring and supports the sockets. Each of the sockets 5 carries a reflector 3, the reflector being here shown as of a socalled angle type, although I do not wish to be limited to the shapes or types of sockets and reflectors here shown. Each of these reflectors houses a lamp 4 supported by the corresponding socket and has a flaring mouth opening obliquely downward. Disposed across this mouth is a color screen 5, here shown in the form of a glass plate. This color screen is supported by an 10 annular ring forming part of the holder arrangement of my invention, and this ring desirably comprises a substantially cylindrical collar portion 6 and an inwardly directed flange 7. The cylindrical or lateral portion 15 6 of the holder ring is desirably of a size freely fitting over the mouth of the reflector and extending slightly upward alongside the reflector beyond this mouth so as to guard against the movement of the holder 20 ring transversely of the said mouth. The inwardly directed flange 7 underhangs the periphery of the color screen 5, but desirably is not in direct contact with the latter. Instead, I preferably interpose a translucent 25 30 cent guard member 8 consisting of clear wire-glass, or glass having a wire mesh embedded therein so as to reinforce the glass against breakage and so as to hold the parts thereof even if breakage should occur.

35 To support this holder ring and to hold the plates or disks 5 or 8 in their normal positions, I desirably employ supporting means connected to some portion of the lighting equipment above the main portion 40 of the reflector and desirably arrange these means so as to afford a yielding support. For this purpose I am here showing the socket 1 as fastened to the conduit 2 by eyebolts 9 extending through the bottom of the 45 conduit and through the flanged base of the socket shell. The eye of each such eyebolt or screw-eye is engaged by two hooks, each of which is at the end of a link portion 10 connected by a spiral spring 11 to a second 50 link portion 12 engaging some part of the holder ring. For this latter purpose, two of the links (namely the ones at the rear of Fig. 1) desirably terminate in hooks arranged as shown at 12^a and snapped through openings 55 13 in the lateral wall 6 of the holder ring, while the other two lower link members 12 are connected by a bight engaging a hook 6 on the front of the holder ring. With this arrangement of the yielding links, the hook 6 and the holder perforations engaged by the two rear links are desirably spaced substantially 120 degrees apart along the periphery of the holder ring to equalize the strains. Thus arranged, the springs 11 60 afford a yielding tension, so that the holder

ring together with the two glass plates supported by it is normally held yieldingly in its operative position by the four yielding links, namely in position in which the two glass plates are disposed in the path of the 70 light projected by the reflector. Then the adjustment automatically afforded by the springs compensates for any irregularities in the size of the various parts, including variations in the thickness of either the 75 guard plate 8 or of the color screen 5.

Furthermore, by detaching the said bight from the hook 6 on the holder ring, the edge of the holder adjacent to this hook can be caused to gap away from the mouth of the 80 reflector so as to permit the color screen to be removed or replaced after the manner shown in Fig. 3. My arrangement therefore permits of the speedy inserting, removing or exchanging of the color screens, so that 85 the desired color effects can be varied quickly and without the use of tools. At the same time, the interposing of the guard plate 8 between the color screen 5 and the outside of the lighting unit serves as a protection 90 against accidents, as this wire-glass guard will continue to support the constituent fragments of the color screen even if the latter should be cracked by the heat of the lamp as 95 sometimes happens.

However, I do not wish to be limited to this particular method of manipulating the holder arrangement for the purpose of inserting, removing or replacing color screens. Neither do I wish to be limited to the particular details of construction or arrangement 100 here disclosed, nor to the use of my invention in connection with sockets bolted to supporting conduits by screw eyes, it being obvious that various modifications might be 105 made without departing from the spirit of my invention or from the appended claims. For example, Fig. 4 shows an embodiment employing only two oppositely disposed yielding links supported by a clamp 13 110 secured to the neck of the reflector, while Fig. 5 shows a more readily portable substitute for the glass color screen, namely a sheet 14 of colored gelatin resting upon the wire-glass guard 5 and held flat by a superposed plate 15 of clear glass.

However, the more simple arrangement shown in Fig. 4 has this disadvantage that a dropping wing or fly may catch on the upper forward edge of the holder ring and hence might damage either the wing or the holder and the plates supported by the latter. I therefore preferably employ at least one link disposed at the front of the reflector where it will act as a fender for guiding a dropping wing or fly past the collar of the holder ring.

Moreover, I do not wish to be limited to the employment of my invention in connection with stage lighting, as it might ob- 130

viously be used with equal facility for other purposes, such as show-window lighting, show-case lighting or the like.

I claim as my invention:—

- 8 1. A lighting unit comprising a lamp, a reflector housing the same, a color screen disposed across the mouth of the reflector, a reinforced glass plate disposed outwardly of the screen, and an annular holder having a portion overlapping the outer face of the glass plate and having another portion housing the peripheries of the said screen, plate and reflector mouth.
- 10 2. A lighting unit comprising a lamp, a reflector housing the same, a color screen disposed across the mouth of the reflector, a reinforced glass plate disposed outwardly of the screen; an annular holder having a portion overlapping the outer face of the glass plate and having another portion housing the peripheries of the said screen, plate and reflector mouth; and yielding means holding the holder in its said position.
- 15 3. A lighting unit comprising a lamp, a reflector housing the same, an annular holder having a collar sleeved over the mouth of the reflector and having a flange extending radially inward of the collar, a transparent reinforcing member resting upon the flange and supported thereby, and a color screen between the lamp and the transparent member and normally clamped against the latter by the collar.
- 20 4. A lighting unit comprising a lamp, a reflector housing the same, an annular holder having a collar sleeved over the mouth of the reflector and having a flange extending radially inward of the collar, a transparent reinforcing member resting upon the flange and supported thereby, and a color screen disposed between the lamp and the transparent member and normally clamped between the said member and the mouth of the reflector.
- 25 5. A lighting unit comprising a lamp, a reflector housing the light emitting portion thereof, a support holding both the lamp and the reflector, an annular holder having a peripheral flange laterally overhanging the mouth of the reflector, a color screen 50 housed by the collar, a transparent reinforcing member also housed by the collar outwardly of the color screen, and connections between the support and the collar for normally holding the collar in its said position and arranged for permitting the collar to be moved out of its said position to allow the replacing of the color screen.
- 55 6. A lighting unit comprising a lamp, a reflector housing the same, a color screen disposed across the mouth of the reflector, a reinforced glass plate disposed outwardly of the screen, a holder movable with respect to the reflector and arranged for holding the screen and plate, and means arranged both for normally retaining the holder in operative position and for preventing a descending object from catching on the holder.
- 70 7. A lighting unit comprising a lamp, a reflector housing the same, a color screen disposed across the mouth of the reflector, a reinforced glass plate disposed outwardly of the screen; an annular holder having a portion overlapping the outer face of the glass plate and having another portion housing the peripheries of the said screen, plate and reflector mouth; and means for holding the holder in its said position and for preventing objects from catching on the free edge of the said peripheral housing portion 75 of the holder.
- 75 8. A lighting unit comprising a lamp, a reflector housing the same, a color screen disposed across the mouth of the reflector, a reinforced glass plate disposed outwardly of the screen; an annular holder having a portion overlapping the outer face of the glass plate and having another portion housing the peripheries of the said screen, plate and reflector mouth; and yielding means 80 holding the holder in its said position, the yielding means including a portion manually detachable from the holder to permit an opening movement of the latter.

Signed at Chicago, Illinois, December 2, 95
1921.

JAMES C. HERRON.
